UNITED STATES PATENT OFFICE

NICOLA GRABICH, OF WEST NEW YORK, NEW JERSEY

LIFE-SAVING DEVICE FOR SHIPS AND THE LIKE

Application filed April 17, 1929. Serial No. 355,881.

This invention relates to certain new and useful improvements in life saving devices for ships, submarines and the like and has particular reference to that class of inventions disclosed in application for patent filed by Nicola Grabich on June 6, 1928, Serial No. 283,335, patented October 1, 1929, No. 1,730,134, and more particularly to improvements on the device in said application.

10 The primary object of this invention is to provide a life saving device in the form of a floating cabin section detachably engaged with the top wall or deck of a ship with novel fastening devices anchoring the cabin in position on the ship and of a watertight nature to prevent the seepage of water into the floating cabin section or ship body when the parts are assembled.

20 The invention specifically relates to a connecting bolt arrangement between the ship body and floating cabin with means engaged with the bolt head to prevent rotation of the bolt during the application of a nut to the threaded end thereof.

25 With the above and other objects in view that will become apparent as the nature of the invention is better understood, the same consists in the novel construction, combination and arrangement of parts to be herein-30 after more fully described, shown in the accompanying drawing and then claimed.

In the accompanying drawing:—

Figure 1 is a fragmentary side elevational view of a ship equipped with the life saving floating cabin section;

Figure 2 is a vertical detail sectional view showing the connecting bolt between the ship deck and cabin floor together with the associated devices;

40 Figure 3 is a detail sectional view taken on line 3—3 of Figure 2 showing the rectangular opening in the deck anchored thimble with the rectangular bolt head held therein against rotation; and

45 Figure 4 is a perspective view of the bolt head engaging thimble.

Referring more in detail to the accompanying drawing, the reference numeral 1 designates a ship of any preferred type, 50 such as a passenger vessel, a submarine or

pleasure craft and is equipped with a buoyant or floating cabin section 2 that is detachably connected thereto, the ship 1 including an upper deck section 3 while the floating cabin section 2 includes a bottom wall or floor 4 flatly seated on the deck as shown in Figure 2.

The connection between the floating cabin section and the ship includes a plurality of bolts extending through the ship deck 3 and cabin floor 4 shown in detail in Figure 2, the headed end of the bolt extending below the ship deck while the nut receiving threaded end of the bolt extending through the deck and floor projects above the cabin floor. 55 A tubular thimble 5 is flared outwardly at its upper end to provide an annular flange 6 provided with openings 7 as shown in Figure 4 for the passage of rivets 8 or the like for anchoring the thimble to the ship deck 3 as shown in Figure 2. The bore of the thimble 5 is rectangular in end elevation as at 9 while said thimble is exteriorly threaded at its lower end as at 10.

70 The bolt 11 is provided with a rectangular head 12 proportioned for sliding and snug reception in the rectangular bore 9 of the thimble as illustrated in Figure 2, the bolt 11 extending upwardly through registering openings 13 in the ship deck 3 and cabin floor 4 and being threaded at 14 at its upper projecting end.

75 A tubular housing 15 closed at its lower end at 16 is internally threaded adjacent its upper end as at 17 for engagement with the threads 10 upon the thimble 5, the upper end of the housing 15 being flanged outwardly and upwardly to provide an annular rim 18 while a gasket 19 is interposed between the rim 18 and ship deck 3 to form 80 a water-tight connection.

85 A nut 20 is threaded on the upper end 14 of the bolt 11 and from an inspection of Figure 2, it will be seen that the ship deck and cabin floor are secured together. A 90 tubular thimble 21 has an outwardly directed flange 22 at its lower end that is anchored to the cabin floor by rivets 23 or the like, the upper end of the thimble being externally threaded as at 24. A cap nut 100

25 is internally threaded as at 26 over a portion of its length for engaging the threads 24 upon the thimble 21, the lower end of the cap nut being flanged outwardly to provide 5 an annular rim 27 disposed adjacent the cabin floor with the gasket 19^a interposed between the rim 27 and cabin floor to provide a watertight joint.

From the above detailed description of 10 the invention, it is believed that the construction and operation will at once be apparent, it being noted that a plurality of bolts 11 and associated devices are provided for anchoring the floating cabin section to 15 the deck of the ship. Separation of the floating cabin from the ship is accomplished within the cabin by first removing the cap nuts 25, then unscrewing the nuts 20 from the bolts 11 and at which time said bolts 20 can be forced downwardly into the housing 15. The cap nuts 25 are then immediately engaged with the thimbles 21 to close the opening 13 in the cabin floor so that no water will be permitted to enter the cabin. 25 The floating cabin may be easily and quickly separated from the ship by assigning the desired number of bolts to a single person for operation, permitting the cabin to float to the surface of the water, should the ship 30 sink or be otherwise incapacitated. The connection between the bolt head 12 and thimble 5 comprising the bore 9 of a configuration similar to the bolt head holds the bolt against rotation during application and 35 removal of the nuts 20 from the bolts.

While there is herein shown and described the preferred embodiment of the invention, it is nevertheless to be understood that minor changes may be made therein without 40 departing from the spirit and scope of the invention as claimed.

I claim:

1. In a life saving device for ships and the like, the combination with a ship body, 45 of a floating cabin section detachably connected to the ship body, the connection comprising a plurality of bolts extending vertically through the ship deck and cabin floor, the bolt head being of polygonal for- 50 mation and disposed below the ship deck, a thimble anchored to the under side of the deck and having a bore of a configura- 55 tion similar to the bolt head with the latter disposed therein to be held against rotation, an elongated housing inclosing the thimble, anchored thereto and having a watertight joint with the lower face of the ship deck, a nut threaded on the upper end of the bolt within the cabin, an exteriorly threaded 60 thimble surrounding the upper end of the bolt and nut and anchored to the cabin floor and a cap nut threaded onto the last named thimble and having a watertight connection with the cabin floor.

65 2. In a life saving device for ships and

the like, the combination with a ship body, of a floating cabin section detachably connected to the ship body, the connection including a plurality of bolts extending upwardly through the ship deck and cabin floor with the head of each bolt being of polygonal formation and disposed below the ship deck, means associated with each bolt head anchored to the lower side of this ship deck permitting sliding movement of 70 the bolt and holding the same against rotation, a watertight hood for the bolt head and associated means, a nut threaded on the upper end of each bolt within the cabin, a thimble surrounding the bolt end and nut 75 and a cap nut detachably engaged with the thimble and having a watertight connection with the cabin floor.

3. In a life saving device for ships and the like, the combination with a ship body, 80 of a floating cabin section detachably connected to the ship body, the connection including a plurality of bolts extending upwardly through the ship deck and cabin floor with the bolt heads disposed below the 85 ship deck, means anchored to the ship deck and engaged with the bolt heads to hold the bolts against rotation, a watertight cover for the bolt heads, a retaining nut on the upper end of each bolt engaged with the 90 cabin floor, a thimble inclosing the nut and anchored to the cabin floor and a cap nut 95 detachably engaged with the thimble and having a watertight connection with the cabin floor.

In testimony whereof I affix my signature.
NICOLA GRABICH.
